IMPROVED BOOT TREE.

WILLIAM AND A. G. KELSEY, OF DELAVAN, WISCONSIN.

Letters Patent No. 59,842, dated November 20, 1866.

SPECIFICATION.

TO ALL WHOM IT MAY CONCERN:

Be it known that we, WILLIAM and A. G. KELSEY, of Delavan, in the county of Walworth, and State of Wisconsin, have invented a new and improved Boot-Tree, and we do hereby declare that the following is a full, clear, and exact description thereof, which will enable others skilled in the art to make and use the same, reference being had to the accompanying drawings forming part of this specification, in which—

Figure 1 is a partial longitudinal section.

Figure 2 is a cross-section in the line xx .

Similar letters of reference indicate like parts.

The nature of this invention consists in a new and improved construction of a boot-tree, which renders it more convenient and powerful for general use in stretching, shaping, and finishing boots.

Upon a bench, A, is secured a stout, upright block, B, on one side of which, in a line with the bench, is attached a centre, C, by means of a pivot end at the base, which passes through and turns in the block, B. The centre, C, differs from ordinary centres in its parallel form and independent construction, permitting the application to it of any common boot-tree, D D, back and front. It is also slotted down the middle from the bottom of the tree to about half way up the calf of the boot leg, as shown in fig. 1, in which slot are pivoted at one end two stretchers, $\alpha\alpha$, which have a close V shape and open outwards at the foot of the boot-tree, by means of a plunger or follower, e, that lies between them, and is connected with and operated by a rod, d, which passes through the centre, C, to the opposite side of the block, B, where it connects with one arm of a knee lever, E, which has its fulcrum on a pin, e, on one side of the bench, A. The other arm of the lever E is connected by a lifting rod, f, with a treadle, F, hung on a bar supported by the legs under the bench.

The treadle F has a catch g on the outer end, which works in a rack h to hold the stretchers $\alpha\alpha$ open when they are operated.

The upper arm of the lever E is connected with the top of the block B by a spiral spring, i, which expands when the treadle F is depressed for opening the stretchers $\alpha\alpha$, by drawing the follower, e, toward their point of connection, and contracts when the treadle is released, thus forcing the follower, e, back, and relieving the pressure of stretchers $\alpha\alpha$ from the boot-tree D D on both sides. The boot-tree is attached to the centre C by slipping the front and back parts upon pins, k k, set in the middle part of the centre, and also against a small guide, l l, which fits in a groove made in their upper ends; the heel and foot of the tree are also connected by a small and powerful spiral spring, m, which is sunk flush in the bottom end, and so attached as to be taken out easily for changing the trees.

It will be seen from this description that when the treadle F is up, the boot-tree will be drawn together by the spring m, and will lie close upon the centre C, and allow a boot to go on the tree readily, and that when the treadle is depressed by the foot, there will be a powerful lever purchase which will draw the follower C up between the stretchers $\alpha\alpha$, and by thus opening them force out the sides of the boot-tree for stretching, shaping, and finishing a boot as required.

The machine is not confined in its application to finished boots, but may be employed advantageously for crimping and stretching tops before they are bottomed.

Having described our invention, what we claim as new, and desire to secure by Letters Patent, is—

The independent centre C, and pivoted stretchers $\alpha\alpha$, in combination with the follower e and rod d; all arranged as herein described, and adapted to operate upon a boot-tree as set forth.

WM. KELSEY,
A. G. KELSEY.
